UNITED STATES PATENT OFFICE.

HARRY G. AINSWORTH, OF KENTLAND, INDIANA.

DOOR-OPERATING MECHANISM.

Application filed November 24, 1922. Serial No. 602,955.

To all whom it may concern:

Be it known that I, HARRY G. AINSWORTH, a citizen of the United States, residing at Kentland, in the county of Newton and

5 State of Indiana, have invented certain new and useful Improvements in Door-Operating Mechanism, of which the following is a specification, reference being had to the accompanying drawings, and to the reference 10 characters marked thereon, which form a part of this specification.

This invention relates to means for opening and closing doors and principally hinged garage doors.

15 The object of the invention is to produce an apparatus, positive in its operation and yet simple in its construction and relatively cheap to manufacture and install.

The attainment of the stated object involves a motor driven sprocket pinion or gear adapted to operate an endless sprocket chain supported upon a swinging arm, one link of the chain being pivotally united to the door to be opened or closed, and an electric circuit for supplying current to the motor from any suitable source of supply, together with switches in the circuit.

25 The invention will be readily understood by reference to the accompanying drawings, 30 in which I have illustrated one embodiment of the invention.

In said drawings,

Fig. 1 is an inside elevation of a pair of hinged doors in a door frame, to which my 35 device is applied, showing the doors open, inwardly.

Fig. 2 is a horizontal or plan sectional view of the same, the section being taken in the plane of the dotted line 2—2 of Fig. 1.

40 Fig. 3 is a top or plan view, enlarged, of the slotted bracket on the swinging door, showing in section the pin on the sprocket engaged in the slot.

Fig. 4 is a perspective view, enlarged, of 45 said bracket and one link of the sprocket chain, by which link the chain is operatively engaged with the bracket.

Fig. 5 is a central, vertical sectional view 50 through the motor driven gears, showing the means for connecting same in operative relation.

In said drawings, A, A' are two doors hinged at 1 to the side members 2 of a door frame or wall opening of a building, so as 55 to swing or open inwardly. M is a motor of any suitable type, electrically connected

in a circuit, indicated by lines C, C, said motor being suitably secured by a bracket 2 above the doors to any fixed support, such as a wall 4.

60 The motor shaft is provided with a worm 5 adapted to actuate a worm gear 6, the latter being loosely mounted upon a shaft 7 rotatively mounted in the bracket 3. Upon said shaft 7 are keyed two sprocket wheels 8 and 9, one above and one below the worm gear 6. The wheel 9 may be coupled to the worm gear 6 by any suitable means, such as the removable bolt 10, shown more clearly in Fig. 5. The gear 6 and wheel 9 remain, 65 normally, coupled so as to be rotated by the motor, but are disconnected by withdrawing the bolt 9 when it is desired to operate the doors manually, as for example when the motor requires repairing or the current for 70 actuating the motor is cut off for any reason.

75 Upon the bracket 3 is mounted one end of an arm D, so arranged as to pivot or swing about the axis of the shaft 7 as a 80 center, the weight of the arm being sustained by any suitable means, such for example as a strut or tie rod 11, connecting the outer end of the arm D with an apertured lug 12 on the bracket 3. The outer or free 85 end of the arm D is provided with a rotatable sprocket wheel 13, of the same size as the sprocket wheel 8, and located in the same plane. About the two sprocket wheels 8 and 13 is passed an endless sprocket chain 14, 90 which will travel continuously in the same direction when the motor is in operation, since the latter will rotate in one direction only.

95 Upon the inside of the door A, near its top margin, is mounted a bracket 14 provided with a projecting lug 16 having an elongated slot 17, the parallel side walls of which extend in a plane parallel with the face of the door. Upon one link only, 18, 100 of the sprocket chain 14, is fixedly secured a downwardly projecting pin or bolt 19 of a size adapted to project into and travel back and forth in the slot 17.

105 From the foregoing description it will be understood that, the door A being open, inwardly, as shown in Figs. 1 and 2, and current having been applied to the motor, the latter will rotate continuously in one direction, say to the right, and motion will be 110 translated to the worm gear 7, sprocket gear 8, sprocket chain 14. The pin-link 18 of the

chain moving with and as part of the chain, will by reason of the pin 19 and its slotted bracket connection 15, 16, 17, pull the door towards the motor, into the closed position, 5 the pivotal arm D swinging easily so that its position relative to the door will constantly change. Any automatic device, of which there are many on the market, may be utilized for stopping the motor at the end of 10 the movement. To open the door and swing it back to the position shown in full lines in Fig. 2, the motor is switched on and will rotate in the same direction as before, when the chain link 18 will travel 15 back on the other side of the arm D, and by its pin 19 connection with the door bracket 15, actuate the door A. The purpose of the slot 17 is to permit the pin 19 to shift its position from one side of the 20 arm D to the other, and pass over the "dead center" at the end of each movement. The length of the slot 17 will be determined, of course, by the diameter or pitch of the 25 sprocket gears 8, 13.

25 A similar unit may be applied to the door A', but it is usually best to actuate the sprocket chains of a pair of doors with a single motor. One means of accomplishing this is shown in Figs. 1 and 2, wherein the 30 shaft 7 of the bracket 3 on each door A, A', is lengthened so as to carry a second sprocket gear 20. The two gears 19, 19, are then connected by the sprocket chain 21. It follows, by thus connecting the operating 35 units on doors A and A', by the chain 21, said doors will move in unison to open or close, as the case may be.

The device above described is very simple, 40 is operated by the mere turning on of a switch in the motor circuit, is positive in its operation, has no complicated parts to get out of order, and is quite cheap to construct and install.

I claim as my invention:

45 1. A device for opening and closing hinged doors, comprising a hinged door, a bracket mounted on a fixed support, a swingable arm mounted at one end on said bracket, a rotatable sprocket gear on each 50 end of said arm, a sprocket chain on said gears, an electrically driven motor on the bracket and operative connections between the motor shaft and one sprocket gear, the 55 door being operatively connected to the sprocket chain.

2. A device for opening and closing hinged doors, comprising a hinged door, a bracket mounted on a fixed support, a swingable arm mounted at one end on said 60 bracket, a rotatable sprocket gear on each end of said arm, a sprocket chain on said gears, an electrically driven motor on the bracket and operative connections between the motor shaft and one sprocket gear, the 65 sprocket chain being connected with the

door by means which shifts its position with respect to the arm as the chain moves along the arm.

3. A device for opening and closing hinged doors, comprising a hinged door, a 70 bracket mounted on a fixed support, a swingable arm mounted at one end on said bracket, a rotatable sprocket gear on each end of said arm, a sprocket chain on said gears, an electrically driven motor on the bracket and operative connections between the motor shaft and one sprocket gear, one of the links of the sprocket chain being 75 operatively connected with the door.

4. A device for opening and closing hinged doors, comprising a hinged door, a 80 bracket mounted on a fixed support, a swingable arm mounted at one end on said bracket, a rotatable sprocket gear on each 85 end of said arm, a sprocket chain on said gears, an electrically driven motor on the bracket, operative connections between the motor shaft and one sprocket gear, a slotted bracket on the door and a pin on one of the 90 sprocket chain links adapted to work in the slot of said bracket.

5. A device for opening and closing hinged doors, comprising a hinged door, a bracket mounted on a fixed support, a 95 swingable arm mounted at one end on said bracket, a rotatable sprocket gear on each end of said arm, a sprocket chain on said gears, an electrically driven motor on the bracket, operative connections between the motor shaft and one sprocket gear and 100 means for disconnecting the same, the door being operatively connected to the sprocket chain.

6. An apparatus for operating two doors 105 hinged to a fixed support, comprising an operating unit for each door consisting of a bracket adapted to be secured to the support and a slotted bracket adapted to be secured to the door, an arm swingingly mounted on the first mentioned bracket, a pair of sprocket gears on the arm, a sprocket chain on the gears, a movable connection between the sprocket chain and the door bracket, one of said units being connected 110 with each door, a motor for driving the sprocket gears of one unit, a second sprocket gear on each unit and a sprocket chain running on said last mentioned sprocket gears, 115 whereby both units are driven from the same motor.

7. In an apparatus for operating hinged doors comprising a motor mounted on a fixed support, an arm pivotally mounted, sprocket gears and a sprocket chain on said 120 arm, a movable connection between the chain and the door, gear connections between the motor and one of the sprocket gears to operate the latter and means for disconnecting said operative gear connections, said means including a rotatable 125

shaft, a motor rotatable worm gear loosely mounted on said shaft, one of the sprocket gears being fixed to rotate with said shaft, and a removable pin engaging the worm gear and one of the sprocket gears.

In testimony that I claim the foregoing as my invention I affix my signature, in the

presence of two witnesses, this 10th day of November, 1922.

HARRY G. AINSWORTH.
